UNITED STATES PATENT OFFICE.

RALPH H. TWINING, OF MARQUETTE, MICHIGAN, ASSIGNOR TO THE CLEVELAND-CLIFFS IRON COMPANY, OF CLEVELAND, OHIO, A CORPORATION OF OHIO.

PROCESS OF AND APPARATUS FOR DISTILLING WOOD.

Application filed December 12, 1924. Serial No. 755,365.

The drawing illustrates in elevation, but more or less diagrammatically, the parts of the apparatus whereby my improved process may be carried out.

5 In the process of wood distillation as commonly practiced, it is customary to subject the vapors from the carbonizing retort after condensation, to repeated distillation or rectification in order to separate out the 10 tar, after which the distilled pyroligneous acid is used for forming acetic acid or mixed with lime to form acetate of lime.

In the distillation of wood, it has heretofore been proposed to expose the vapors 15 from the carbonizing retort to the scrubbing action of tar oil in order to aid in separating out the tar from the pyroligneous acid. Serious objections have been found in practice to this process. In the 20 first place, the vapors passing through the scrubber take up and carry over with them to the condenser, in mechanical suspension, an excessive amount of tar; and moreover, such excess of tar renders this distillate unsuitable for immediate treatment with lime 25 and unsuitable also for rectification, as the tar tends to plug up or clog the rectifying apparatus.

The object of my invention is to overcome 30 the above objections and to produce at a materially reduced cost a pyroligneous acid suitable for direct distillation in the manufacture of acetic acid and for the direct manufacture of acetate of lime.

To this end, the invention consists primarily in subjecting the vapors from the carbonizing retort to the action of "green liquor" (pyroligneous acid) from which the tar has to a large extent been separated. 40 The manner of carrying out my invention will be hereinafter described and the distinctive features of the invention pointed out in the claims at the end of the specification. While I have illustrated in the drawing an apparatus well adapted for the practice of my invention, it will be understood that the details of the apparatus may be varied widely by those skilled in the art.

The accompanying drawing illustrates 50 somewhat diagrammatically the preferred form of the improved apparatus.

Referring to the drawing, A designates the carbonizing retort from which the vapors will be conducted by a pipe 2 to the lower portion of a scrubber B. This scrub-

ber may be of any familiar or suitable construction, being preferably a tower lined with "checkerwork" of vitrified brick. From the bottom of the scrubber B leads a pipe 3 to a suitable trap 4 and from this trap 4 leads a pipe 5 to a pipe 6 that connects with a suitable pump C. The pipe 6 connects with the bottom of the off-take pipe 2 that extends between the retort and the bottom of the scrubber B and the pipes 3 and 6 serve to carry off the tar and the unvaporized portion of the scrubbing liquor respectively from the bottom of the scrubber and from the bottom of the pipe 2. The liquor and tar thus delivered to the pump 70 C is forced thence by pipe 7 to the settling stills or tanks D, D' and D² (in suitable number), these stills or tanks being heated by steam coils indicated by dotted lines in the drawing. The liquor within the settling stills or tanks is maintained preferably at about the boiling point thereof, viz, from 100 to 120 degrees C. From the bottoms of the settling stills or tanks D, D' and D², short branch pipes 8, 9 and 10 lead 80 to a main pipe 11 that connects with a pump E from which the settled tar will be forced by a pipe 12 to a suitable tar receptacle (not shown). Preferably, pipes 5, 6, 8, 9 and 10 will be provided respectively 85 with suitable valves 5^a, 6^a, 8^a, 9^a and 10^a.

From the top of the scrubber B the vapors are passed to the top of a condenser F, this condenser being of any familiar or suitable construction, and from the bottom of the condenser F leads a pipe 14, preferably furnished with a trap 15, to the tank G, in which the green liquor will be collected. From the bottom of the tank G a pipe 16 will conduct the green liquor to a neutralizing tank (not shown). Preferably, a pipe 17 connected to the pipe 14 leads to a point beneath the bottom of the retort for taking off the non-condensable gas and supplying it as a part of the fuel whereby the retort is exteriorly heated. From the bottom of the tank G, a pipe 20 (preferably formed with a trap 21) and having a valve 22, leads to the top of one of the settling stills or tanks D² and the upper portions of the several stills D, D' and D² are connected together by the pipes 23 and 24. Hence it will be seen that a portion of the distillate or green liquor collected in the tank G will pass thence to the several settling stills 110

or tanks D, D' and D², so as to maintain a proper supply of liquor in such tanks at or above the level of the pipes 23 and 24. From the tops of the settling stills or tanks 5 extend respectively the pipes 25, 26 and 27, these pipes being furnished with valves 25^a, 26^a and 27^a, and leading to a condenser H that may be of any suitable construction. From the bottom of the condenser H, a pipe 10 28 leads to the tank G. The purpose of the condenser H is to condense the vapors passing from the tops of the settling stills or tanks D, D' and D². A pipe 29 connects the upper portion of the settling still or tank 15 D² with the pump K and from this pump green liquor is forced by the pipe 30 to the top of the scrubber B where it will be delivered preferably through a suitable spray 31 over the top of the "checkerwork" 20 interior of the scrubber. Suitable valves 29^a and 30^a are provided in the pipes 29 and 30.

From the foregoing description, it will be seen that my invention is carried out by the apparatus shown, as follows:—As the vapors 25 from the retort A are delivered by the pipe 2 into the bottom of the scrubber B, they will pass upward through the "checker-work" of the scrubber and in so doing will be exposed to the down flowing green liquor 30 delivered to the top of the scrubber. In thus passing through the scrubber, the temperature of the vapors is very materially reduced as the vapors issue from the retort at about 650° F. and enter the condenser F 35 at approximately 212° to 250° F. The green liquor delivered at the top of the scrubber passing down through the body of the scrubber carries with it a large proportion of the tar and condensed products, while the 40 uncondensed vapors pass to the condenser F where, being largely free from tar, their condensation results in a pyroligneous acid (herein termed green liquor) suitable for direct distillation in the manufacture of 45 acetic acid, and also well suited for the direct manufacture of acetate of lime.

Crude pyroligneous acid consists substantially of wood spirits 3 to 4 per cent, acetic acid 6 to 10 per cent, dissolved tar 3 to 6 50 per cent, settled tar 10 to 15 per cent, and the remainder water. The scrubbing liquor used in the present process is crude pyroligneous acid or so-called "green liquor" from 55 which the settled tar has been removed. It is passed into the scrubber at about its boiling point, namely, about 100 degrees C., and in such copious quantities that, while it condenses and carries down mechanically practically all of the tarry and tar-forming 60 ingredients of the retort vapors, and although most of the wood spirits and some of the acetic acid are distilled from the liquor in the scrubber, the greater portion of the liquid withdrawn from the scrubber and 65 passed to the settling tanks is crude pyrolig-

neous acid or "green liquor." If the liquor in the lower portion of the scrubber were largely tarry products, the operation would be subject to much the same defects as previously mentioned when tar or tar oil is employed for scrubbing, namely, the retort gases and vapors would pick up and carry over mechanically a considerable amount of the tarry products and tar would accumulate in the scrubber and other parts of the apparatus.

Because of its comparatively low boiling point, the pyroligneous acid scrubbing liquor absorbs a great deal of heat from the retort gases and so effectively condenses the tarry and the tar-forming products in the gases. This action is aided because of the absorption of heat by the evaporation of most of the wood spirits and some of the acid and water in the scrubbing liquor and the spirits and acid thus evaporated, as well as the retort gases, are thereby freed from tar. The tarry products picked up from the retort gases in the scrubber as well as that formed from the ingredients of the pyroligneous acid liquor, are removed by settling in the settling tanks and the liquor thus freed from settled tar is again used in the scrubbing operation. The losses due to evaporation in the scrubbing operation and in the settling tanks are made up, as stated, by additions of pyroligneous acid or "green liquor" from the condensing apparatus, so that the body of circulating liquor is maintained in the desired volume and also is restored to substantially its original composition.

In practice, it has been demonstrated that the scrubbing of the vapors with green liquor insures the separation therefrom of a large proportion of the tar and avoids the danger of any accumulation of tar upon the checkerwork of the scrubber or within the condenser.

By arranging the settling stills in series, as shown, and as I prefer to do, a better opportunity is afforded for the tar to settle before it is pumped off to the tar receiving tank.

Inasmuch as the vapors from the retort are delivered to the bottom of the scrubber at a very high temperature, the heat of these vapors serves to produce within the scrubber a distilling action which aids in freeing in great measure the green liquor delivered to the top of the scrubber from such tar and tarry oils as may be carried thereby and contained therein. This vaporization of the green liquor which is being pumped from the settling stills D, D' and D² tends to decrease the quantity of liquor within the settling stills or tanks, but this is compensated for by the supplying of additional green liquor to such settling stills or tanks from the tank G. The operator in control of the apparatus, by manipulating the valves

between the tank G and the settling still or tank D², can readily regulate the flow of green liquor from the tank G to the settling stills or tanks, so as to maintain a full supply of such liquor at all times within such tanks. This supply of liquor from the tank G will also serve to replace the tarry products that are drawn off from the bottoms of the settling stills or tanks. It will thus be seen that the process is a continuous one and the pyroligneous acid issuing from the tank G is so free from tar and tarry oils that it is well adapted for use without further distillation in the production of acetic acid or acetate of lime.

It will be understood that the practice of my invention may be varied as to details and that features of the invention may be employed without its adoption as an entirety.

Having thus described my invention, what I claim as new and desire to secure by Letters Patent is:—

1. The process of distilling wood which consists in subjecting the vapors, as they issue from the retort, to the countercurrent scrubbing action of hot crude pyroligneous acid resulting from such distillation and from which tar has been settled.

2. The process of distilling wood which consists in passing the vapors from the retort and crude pyroligneous acid in opposite directions through a scrubber, withdrawing liquor from the scrubber, and after settling tar therefrom, returning the liquor to the scrubber.

3. The process of distilling wood which consists in passing the vapors from the retort and crude pyroligneous acid in opposite directions through a scrubber, withdrawing liquor from the scrubber, and after separating tar therefrom, returning the liquor to the scrubber, condensing the vapors passing from the scrubber and employing a portion of the resultant liquor for maintaining a supply of scrubbing liquor.

4. The process of distilling wood which consists in scrubbing the vapors from the retort with a circulating body of crude pyroligneous acid, withdrawing tar from the body of scrubbing liquor and adding crude pyroligneous acid thereto to maintain its supply.

5. An apparatus for distilling wood comprising the combination of a carbonizing retort, a scrubber connected to said retort, a condenser connected to said scrubber, a settling still connected to the bottom of said scrubber to receive tar and unvaporized portions of the scrubbing liquor from said scrubber, means for conducting a portion of the distillate from the condenser to said settling still, means for delivering the liquor from the upper portion of said settling still to the top of said scrubber, a supplemental

condenser for condensing the vapors from said settling still, and means for connecting said supplemental condenser to the top of said settling still.

6. An apparatus for distilling wood comprising the combination of a carbonizing retort, a scrubber connected to said retort, a condenser connected to said scrubber, a series of settling stills connected to the bottom of said scrubber and adapted to receive tar and the unvaporized portion of the scrubbing liquor from said scrubber, means for conducting a portion of the distillate from the condenser to said settling stills, means for delivering the liquor from the upper portion of said settling stills to the top of said scrubber, a supplemental condenser, and means for connecting said supplemental condenser to the tops of said settling stills.

7. In the art of wood distillation, the process which consists in scrubbing the hot vapors from the retort with a circulating body of hot, crude pyroligneous acid to thereby remove the tarry products and partially vaporize the scrubbing liquor, condensing the vapors resulting from the scrubbing action, settling out tar from the liquor resulting from the scrubbing action and adding fresh crude pyroligneous acid to the circulating body of scrubbing liquor to maintain its supply.

8. In the art of wood distillation, the process which consists in passing the hot vapors from the retort successively through a scrubber and then through a condenser, circulating a body of crude pyroligneous acid through the scrubber and a heated settling tank and back to the scrubber and thereby effecting the removal of tar from the retort vapors and the partial vaporization of the crude pyroligneous acid in the scrubber and the separation of tar from the body of circulating scrubbing liquor in the settling tank, and adding fresh crude pyroligneous acid from the condenser to the body of circulating scrubbing liquor to maintain its supply.

9. In the art of wood distillation, the process which consists in subjecting the hot retort gases and vapors to the counter-current scrubbing action of crude pyroligneous acid to thereby separate tarry products from the retort vapors and gases, removing the tarry products and unvaporized scrubbing liquor to a settling tank and separately withdrawing the settled tar and the pyroligneous acid liquor employed in the scrubbing operation from the settling tank.

10. In the art of wood distillation, the process which consists in passing the hot retort gases and vapors and hot crude pyroligneous acid through a suitable counter-current apparatus to remove tarry products from the retort vapors, withdrawing the

scrubbing liquor and tarry products, settling out the tar and again using the liquor in the counter-current apparatus.

11. In the art of wood distillation, the process which consists in passing the hot retort vapors and gases and hot crude pyroligneous acid through a suitable counter-current scrubbing apparatus to remove tarry products from the retort vapors, withdrawing and condensing the vapors from the counter-current apparatus, withdrawing the pyroligneous liquor and the tarry products from the counter-current apparatus and, after separating out the tar therefrom, re- using the liquor in the counter-current apparatus and maintaining the supply of scrubbing liquor by adding a portion of the pyroligneous acid produced by condensing the vapors.

12. In the art of wood distillation, the process which consists in passing the hot retort vapors and gases through a suitable scrubbing apparatus and then through a suitable condensing apparatus, circulating a body of crude pyroligneous acid continuously and repeatedly through the scrubbing apparatus and a heated settling tank and thereby effecting the removal of tar from the retort vapors in the scrubbing apparatus and the separation of tar from the body of circulating pyroligneous acid in the settling tank, and adding fresh pyroligneous acid from the condensing apparatus to the body of circulating scrubbing liquor to maintain its supply.

13. Apparatus for distilling wood comprising a carbonizing retort, a scrubber connected thereto, a condenser connected to said scrubber, a settling tank connected to the bottom of the scrubber for receiving unvaporized scrubbing liquor and tar there-

from, means for conducting a portion of the liquor from the condenser to said settling tank, means for withdrawing tar from the bottom of the settling tank and means for 45 delivering scrubbing liquor from the upper portion of the settling tank to the top of the scrubber.

14. In wood distillation, the process of removing tarry products from the hot retort vapors which comprises repeatedly using a body of crude pyroligneous acid to effect a counter-current scrubbing of the hot retort vapors and separately and repeatedly settling and removing from the scrubbing 55 liquor the tarry products picked up in the scrubbing operations.

15. In wood distillation, the process of removing tarry products from the hot retort vapors which comprises scrubbing such 60 vapors in a counter-current of hot crude pyroligneous acid, withdrawing the resultant pyroligneous acid liquor and tarry products and, after settling out the tarry products, using the said liquor for again scrubbing 65 hot retort vapors.

16. In wood distillation, the process of removing tarry products from the hot retort vapors which comprises repeatedly circulating a body of hot crude pyroligneous 70 acid through suitable counter-current scrubbing apparatus and a suitable settling apparatus to thereby remove tarry products from the hot retort gases in the scrubbing apparatus and separate the tar from said 75 body of scrubbing liquor in the settling apparatus, and adding fresh crude pyroligneous acid to the circulating body of scrubbing liquor to compensate for the portion of the liquor evaporated in the scrubbing operations.

RALPH H. TWINING.
